Primary Examiner — Holly E Thurman*Assistant Examiner* — Bailey M Knotts(74) *Attorney, Agent, or Firm* — Sinorica International Patent & Trademark(57) **CLAIM**

The ornamental design for a ceiling fan light kit, as shown and described.

DESCRIPTION

FIG. 1 is a front top perspective view of a ceiling fan light kit showing my new design;

FIG. 2 is a front elevational view thereof;

FIG. 3 is a rear elevational view thereof.

FIG. 4 is a left side elevational view thereof;

FIG. 5 is a right side elevational view thereof;

FIG. 6 is a top plan view thereof;

FIG. 7 is a bottom plan view thereof;

FIG. 8 is a front bottom perspective view thereof; and,

FIG. 9 is another front top perspective view thereof, but showing the light kit fixed to the broken line showing of a ceiling fan.

The broken lines illustrate portions of the ceiling fan light kit that form no part of the claimed design.

1 Claim, 7 Drawing Sheets(56)
